VALVE FOR INFLATABLE BOATS

John C. Crowley, Cleveland Heights, Ohio, assignor to The Dill Manufacturing Company, Cleveland, Ohio, a corporation of Ohio

Application May 14, 1942, Serial No. 442,929

8 Claims. (Cl. 137—144)

This invention relates to a valve mechanism and more particularly to a valve mechanism for an inflatable boat or raft. It will be understood, however, that a valve mechanism embodying the present invention may be advantageously employed in other environments wherever it is desired to introduce fluid or gas simultaneously into separate compartments at an equal rate and volume.

An object of the invention is to provide a valve mechanism of the type which includes a plurality of separate valve elements controlling the simultaneous introduction of gas or fluid into a plurality of separate compartments and which mechanism includes means for actuating all of the valve elements concurrently and exactly the same.

Another and more specific object is to provide a valve mechanism for controlling the introduction of fluid or gas into the separate compartments of an inflatable boat or raft and which mechanism embodies valve elements and means for actuating the same in unison and exactly alike, wherefore the separate compartments of the boat or raft may be inflated at the same rate and to the same extent from a common source of fluid or gas.

A further object of the invention is to provide a valve mechanism of the character referred to in either of the above mentioned objects and which mechanism is efficient in operation, simple in construction and so designed as to be readily manufactured and assembled.

Further and additional objects and advantages not hereinbefore referred to will be pointed out or become apparent hereinafter during the following detailed description of several embodiments of the invention which are illustrated in the accompanying drawings, wherein

Fig. 1 is a top plan view of an inflatable boat or raft to which a valve mechanism embodying the invention is applied, a portion of the outer surface of the boat being broken away and shown in section to reveal an underlying portion.

Fig. 2 is a side elevational view of the boat or raft shown in Fig. 1.

Fig. 3 is a detached view on a larger scale than Figs. 1 and 2 of the valve mechanism embodying the invention and shows the protective and attaching envelope of the mechanism in section and the manifold housing of the mechanism enclosed in said envelope in elevation.

Fig. 4 is a longitudinal sectional view through the manifold housing of the valve mechanism

shown in Fig. 3 and is taken substantially on line 4—4 of Fig. 5 looking in the direction of the arrows.

Fig. 5 is a top plan view of the manifold housing shown in Fig. 4.

Fig. 6 is a transverse sectional view through the manifold housing of the valve mechanism and is taken substantially on line 6—6 of Fig. 4 looking in the direction of the arrows.

Fig. 7 is a transverse sectional view through the manifold housing of the valve mechanism and through one of the valve elements mounted in said housing and is taken substantially along line 7—7 of Fig. 4 looking in the direction of the arrows.

Fig. 8 is a longitudinal sectional view through the attaching and protecting envelope and the manifold housing of a different form of valve mechanism embodying the invention than has been illustrated in the previous views, the section being taken along line 8—8 of Fig. 11 looking in the direction of the arrows, while a portion of the lower end of one of the valve elements is shown in elevation.

Fig. 9 is a transverse sectional view through the manifold housing and one of the valve elements of the valve mechanism shown in Fig. 8, the attaching and protecting envelope thereof being omitted, and is taken substantially along line 9—9 of Fig. 8 looking in the direction of the arrows.

Fig. 10 is a transverse sectional view through the manifold housing of the valve mechanism shown in Fig. 8 and is taken substantially along line 10—10 of Fig. 8 looking in the direction of the arrows, and

Fig. 11 is a top plan view of the valve mechanism shown in Fig. 8.

The valve mechanisms have been shown in the drawings as applied to an inflatable raft or boat for purposes of illustration since said mechanisms have particular utility when so used. It will be understood, however, that the valve mechanisms may be advantageously employed with other apparatus wherein it is desired to introduce fluid or gas from a common source of supply simultaneously into a plurality of separate compartments and at equal rates and equal volumes.

The boat or raft shown in Figs. 1 and 2 is an inflatable one and is of the type carried by aircraft, ships and the like in normally deflated condition for inflation and use in case of an emergency. The boat or raft is constructed of

rubberized fabric and the laps and seams of the boat are secured by cement so as to eliminate stitching or metal securing members from its construction. The boat or raft comprises an encircling buoyant or floatation tube indicated generally at 15 and a fabric bottom 16 secured to the underside of the buoyant or floatation tube 15 and extending across the space formed by the tube. The floatation tube 15 is divided along its horizontal center line by a horizontal bulkhead 17 into an upper compartment 18 and a lower compartment 19 which are separate from each other and are individually inflatable. In some instances the boat or raft may be divided into additional compartments by vertical bulkheads, but such an arrangement is immaterial to a description of the present invention.

As stated, the boat or raft is inflatable and the inflation of the boat is usually accomplished, particularly in emergencies, by the simultaneous introduction into the separate compartments thereof of gas under pressure from a common cylinder or container, which latter is indicated at 20. The boat or raft may be provided with valves 21 communicating, respectively, with the separate compartments and providing for manual pressure relief of the compartments or the inflation thereof by means of a hand pump or by an air hose.

The valve mechanism embodying the present invention is intended to be used for the concurrent inflation of upper and lower compartments of the boat by gas released from a common cylinder or container 20. The cylinder 20 contains gas under suitable pressure, such gas usually being CO₂ and the discharge end of the cylinder is connected to a cylinder valve 22 of known construction and provided with manually operated means for rupturing the seal in the discharge end of the cylinder, all as will be well understood. The cylinder valve 22 is connected to the inlet nipple 23 of the valve mechanism embodying the present invention by suitable connecting means including the connecting nut 24, all as will be understood since it is common practice in the art.

Heretofore the practice has been to employ a valve mechanism permanently secured to the raft or boat and including a common chamber in communication with the inlet nipple of the mechanism and having two outlets controlled by separate valve elements and communicating, respectively, with the separate upper and lower compartments of the inflatable raft or boat. The valve elements employed in such a valve mechanism are normally maintained seated by spring pressure and are opened by the pressure of the gas released from the cylinder and entering the common chamber. Difficulty has been encountered in the use of such a valve mechanism since the valve elements thereof do not always operate uniformly under the pressure of the incoming gas, due primarily to the fact that the spring pressures on the valve elements cannot be maintained equal and also for other reasons as, for example, sticking or freezing of the valve elements. The result is that in many instances of inflating boats or rafts of this type the separate compartments thereof are not inflated at the same rate and to the same extent from the common source of supply of pressure fluid, with a consequent decrease in the effectiveness of the boat when inflated.

The valve mechanism embodying the present invention overcomes these defects, since the sepa-

rate valve elements thereof are operated simultaneously at equal rates and to the same extent by the pressure of the gas coming from the cylinder into the common chamber of the valve mechanism. This means that the separate upper and lower compartments of the boat will always be inflated to the same extent and at the same rate. It also means that the practical difficulty of procuring and using springs of exactly the same strength and tension and capable of maintaining such conditions for normally seating the valve elements of the valve mechanism is eliminated, since in the mechanism of the present invention the valve element springs do not have to possess or maintain exactly the same strength and tension.

The valve mechanism shown in Figs. 3 to 7 inclusive will now be described. The valve mechanism comprises a manifold housing consisting of the two separable parts 25 and 26 secured together by suitable securing screws 27 the heads of which are countersunk in the part 25. A gasket 28 is clamped between the two parts 25 and 26 of the manifold housing to seal the interior thereof. The part 25 is illustrated as substantially of inverted cup shape and is provided centrally thereof with a raised dome 29 in which is located the inlet nipple 23. The part 25 of the manifold housing is enclosed or covered completely by a protecting envelope 30, except that access is provided to the inlet nipple 23 so the cylinder valve can be connected thereto by the connecting nut 24 while openings 30a in the envelope align with the heads of the screws 27. The part 26 of the manifold housing is illustrated as substantially a rigid plate provided with spaced threaded openings into which are screwed identical plugs 31 constituting part of the valve elements and which extend above and below the plate. The part 26 is enclosed in a protecting and attaching envelope 32 which extends around the side edges of the part 26 and beneath the same but is provided with suitable openings through which the plugs 31 extend. The envelope 32 is provided with an attaching flange 33 which, together with the under surface of the envelope 32, is secured by cement or other suitable means to the material of the upper surface of the floatation or buoyant tube 15 adjacent the bow of the boat or raft. The envelopes 30 and 32 are formed preferably of rubber and are cemented or otherwise suitably secured to the parts 25 and 26 of the manifold housing. When the parts 25 and 26 are clamped together by the screws 27 the contacting edges of the envelopes 30 and 32 will be in engagement with each other with a sealing relationship.

The plugs 31 are provided at their upper or inner ends and within the manifold housing with openings or bores 34 which communicate with counterbores 35 which have tapered portions 36 adjacent the openings 34 and extend to the outer or lower ends of the plugs 31. The plugs 31 are provided at their lower or outer ends with conical shoulders 37 about which the upper edges of substantially cup-shaped retaining members 38 are clamped. The retaining members 38 are protectively coated with rubber or other suitable material 39 so there will be no exposed metal parts extending into the boat or raft. The retaining members 38 and their protective coatings 39 are provided with openings 40, it being understood that the interior of one of the retaining members through the openings 40 is in direct communication with the upper compartment 18

of the raft, while the interior of the other retaining member 38 through its openings 40, is in communication with the lower compartment 19 through a conduit or tube 41 connected to such retaining member.

In each plug 31 there is mounted a movable valve member which comprises an enlarged portion 42 located in the counterbore 35 and a reduced pin portion 43 extending from the inner or upper end of the enlarged portion 42 and through the opening or bore 34 and into the interior of the manifold housing. A valve gasket 44 is mounted on the upper end of the enlarged portion 42 surrounding the pin 43 and is adapted to sealingly engage the tapered upper or inner end portion 36 of the counterbore 35 in the plug 31. The enlarged portion 42 of the valve member is provided with a recess into which extends a coil spring 45, the lower end of which surrounds a pin 46 extending upwardly from the bottom of the retaining member 38. It will be seen that the spring 45 since it abuts at one end the bottom of the fixed retaining member 38 and at its other end the valve member, acts to normally maintain the valve gasket 44 seated against the tapered end portion 36 of the counterbore 35. The construction just described is common to both plugs 31 and constitutes what is designated herein as a valve element of the mechanism.

The part 26 of the manifold housing is provided with a recess 47 which communicates with a concentric and larger recess or counterbore 48 extending to the upper or inner surface of the part 26. The recess or counterbore 48 is surrounded by an annular groove which receives the peripheral bead formed on a flexible diaphragm 49 and which diaphragm is clamped in position by a ring 50 secured to the inner surface of the part 26 by suitable clamping screws 51.

A post 52 has a reduced threaded portion which extends through a central opening in the diaphragm and receives a nut 53 which acts to clamp the diaphragm between the post 52 and a thin washer 54. The post 52 also has a reduced threaded part 55 extending from its upper end and into the interior of the dome 29 of the part 25. The threaded extension 55 passes through a central opening formed in an equalizer bar 56 and into a clamping nut 57 which when screwed down on the extension 55 clamps the equalizer bar 56 in position on the post 52. The nut 57 is square and the corners thereof have sliding engagement with the interior wall of the dome, thus guiding the nut and assuring vertical movement without tipping of the bar 56.

The equalizer bar 56 extends longitudinally of the manifold housing and parallel to the inner surface of the plate-like part 26 thereof. The opposite reduced ends of the equalizer bar 56 overlie at equal distances the inner or upper ends of the pins 43 of the movable valve members.

It will be seen that when pressure fluid enters the interior or chamber of the manifold housing through the inlet nipple 23 and the interior of the dome 29 the flexible diaphragm 49 is subject to the pressure created within the manifold housing or chamber by the pressure fluid and will be flexed thereby in a downward direction as viewed in the drawings, with a resultant bodily downward movement of the equalizer bar 56. The downward movement of the equalizer bar 56 causes the opposite ends of said bar to engage simultaneously with the upper or inner ends of the pins 43 of the movable valve members of the valve elements and a continuation of this movement of

the equalizer bar moves said members in unison to the same extent and at the same rate and pressure against the action of the springs 45 to unseat the valve gaskets 44 of the movable valve

5 members to an equal extent, thus providing exactly the same areas through the plugs 31 of the valve elements for the passage of pressure fluid therethrough and into the separate upper and lower compartments of the inflatable raft or boat.

10 The result is that said compartments are inflated simultaneously from the common source of supply, i. e., the cylinder 20 to the same degree and at the same rate.

Although the pressure of the incoming fluid 15 in the chamber of the manifold housing effects the opening of the valves this pressure does not act on the valves individually, but the latter are actuated simultaneously and equally by the pressure through a common mechanical means, i. e., the equalizer bar 56. Consequently the valve elements are opened simultaneously and to the same extent, irrespective of any variation in the strength of the springs 45 or any other reason which might tend to cause one valve element to open more readily than the other.

The form of valve mechanism embodying the invention and shown in Figs. 8 to 11 inclusive differs from the previously described form in that the protective and attaching rubber envelope 58 20 for the mechanism is formed integral throughout and once it is attached to the manifold housing of the valve mechanism the separate parts of said housing may not be separated without removing the envelope 58 therefrom. The envelope 58 is a molded rubber one and is provided with an attaching flange 59 by which the valve mechanism is cemented or otherwise secured to the raft or boat.

The manifold housing of the valve mechanism 30 shown in Figs. 8 to 11 inclusive comprises a chambered part 60 and a closure plate 61. The part 60 is provided with a longitudinally extending chamber 62, access to which may be had prior to securing the envelope 58 on the 35 manifold housing from the end of the part through a threaded opening which can be closed by a threaded sealing plug 63.

The part 60 is transversely enlarged intermediate its ends, as indicated at 64, and this enlarged portion of the part is provided on the upper side thereof with a dome 64a, the upper end of which merges into the inlet nipple 65, similar to the inlet nipple 23 of the previously described form. The part 60 is provided with 45 openings 66 which communicate with the chamber 62 adjacent the opposite ends of the latter and which also communicate with threaded counterbores that extend to the outer or lower face of the part 60 and are provided at their inner ends with a straight shouldered portion 67 and a tapered portion 68. The part 60 is also provided centrally thereof and in alignment with the dome 64a with an opening 69 forming a continuation of the interior of the dome and extending perpendicularly to the chamber 62. The opening 69 at its lower end, as viewed in the drawings, is in communication with a counterbore 70 formed in the part 60 and having its bottom or inner end provided with an annular groove to receive a bead or flange formed on the circumference of a flexible diaphragm 71 which extends across the bottom of the counterbore 70 and the adjacent end of the opening 69. A clamping ring 72 mounted in said counterbore acts to 55 clamp the diaphragm 71 in position.

In each threaded counterbore which communicates with the openings 66 in the part 60 there is screwed a threaded plug 73 until the inner end of said plug contacts the straight shouldered portion at the inner end of the counterbore. The plugs 73 are provided with external flanges 74 which engage with the closure plate 61 and act when the plugs are completely screwed into position in the counterbores to hold said plate clamped against the lower side or surface of the part 60 and against the retaining or clamping ring 72 for the diaphragm 71 previously referred to.

The plugs 73 are provided with straight bores 75 extending therethrough and at their lower ends have external conical shoulders 76 about which the upper edges of substantially cup-shaped retaining members 77 are clamped. The retaining members 77 are protectively coated with rubber or other suitable material 78 and said members and said material are provided with openings 79.

Movable valve members 80 are mounted in the bores in the plugs 73 with a clearance therebetween and said members are provided at their lower ends, as viewed in the drawings, with recesses into which extend valve springs 81. The valve springs 81 abut at one of their ends against the members 80, while their opposite ends abut the retaining members 77 and surround pins 82 carried thereby. The valve members 80 are provided at their inner or upper ends with pins 83 extending with a clearance through the openings 66 in the part 60 and into the chamber 62. Valve gaskets 84 are mounted on the inner or upper ends of the valve members 80 and are normally held seated against the tapered shoulder portions 68 by the springs 81 as will be clearly understood.

A post 85 is located in the opening 69 and is provided on its lower side as viewed in the drawings with a reduced threaded portion 86 which has screwed thereon a nut 87 that serves to clamp the diaphragm 71 and a thin washer 88 between the lower end of the post 85 and the nut 87. The plate-like part 61 of the housing is provided with a recess 89 to accommodate the nut 87 when the diaphragm 71 is flexed downwardly. The post 85 on its upper end is provided with a reduced threaded extension 90 that screws into a threaded bore 91 formed in a block 92 that extends from the opening 69 into the interior of the dome 64a.

The block 92 is provided with a threaded bore and an enlarged counterbore communicating therewith and both extending transversely of the block and perpendicularly to the threaded opening 91 therein. A rod 93 is provided with a threaded portion 94 which screws into the threaded bore in the block 92 and also with an enlarged cylindrical portion 95 adjacent said threaded portion 94 and which interfits the enlarged counterbore in the block 92 and imparts stability to the rod 93 and maintains the same perpendicular to the vertical axis of the block 92 and post 85. The rod 93 at its left hand end as viewed in the drawings is provided with a transverse screwdriver slot 96 which is utilized in assembling the rod in the chamber 62 of the housing and in screwing the rod into position in the block 92, it being understood that the rod is so arranged in the chamber before the envelope 53 is applied to the manifold housing and when the nut 63 is removed from the opening in the end of the latter. The rod 93 over-

lies the inner ends of the pins 83 of the movable valve members and is equally spaced from said ends of the pins. The block 92 is square and the corners thereof have sliding contact with the interior wall of the dome 64a to guide the block in its vertical movement and prevent tipping of the rod 93.

It will be recalled that the plate-like part 61 of the manifold housing is secured in position against the underside of the part 60 by the plugs 73 when the latter are screwed into assembled position.

It will also be understood that when the inlet 65 is connected to a source of supply of pressure fluid, as for example, the cylinder CO₂ and the fluid flows into the interior of the dome 64 and the chamber 62 of the manifold housing the pressure created thereby deflects the diaphragm 71 and moves the post 85 and block 92 downwardly with a resultant movement of the rod 93 into engagement with the inner ends of the pins 83 of the movable valve members. This downward movement of the post 85, block 92 and rod 93 continues and effects the unseating of the valve gaskets 84 with respect to the tapered shoulders 68, thus allowing the pressure fluid to flow through the openings 66 and through the plugs 73 and thence into the compartments of the inflatable raft or boat.

In the present embodiment, as in the first described embodiment, the valve elements will be actuated mechanically in unison and identically the same in response to the pressure created in the chamber 62 by the incoming pressure fluid. Therefore any inequalities in the tension of the valve springs 81 or any other cause which might render one valve element harder to open than the other will not result in unequal inflation of the separate compartments of the raft or boat, since both valves are opened by the rod 93 in unison and identically the same.

Although several preferred embodiments of the invention have been illustrated and described herein it will be understood that the invention is susceptible of various modifications and adaptations within the scope of the appended claims.

Having thus described my invention I claim:

1. A valve mechanism of the character described, comprising a housing having a chamber therein and provided with an inlet to said chamber from a source of pressure fluid and with a plurality of outlets from said chamber, normally closed valve elements operatively associated with said elements, and means responsive to the pressure created in said chamber by the incoming pressure fluid for actuating mechanically said valve elements to open position simultaneously and identically and including a flexible diaphragm and a bar operatively associated therewith and with all of said valve elements and movable in the same direction as said diaphragm.

2. A valve mechanism of the character described, comprising a housing having a chamber therein and provided with an inlet to said chamber from a source of pressure fluid and with a plurality of outlets from said chamber, normally closed valve elements operatively associated with said outlets, and means responsive to the pressure created in said chamber by the incoming pressure fluid for actuating mechanically said valve elements to open position simultaneously and identically and including a flexible diaphragm, a block operatively connected therewith, and a rod removably connected with said block

and operatively associated with all of said valve elements.

3. A valve mechanism as defined in claim 2 and wherein said housing is provided with an opening affording access to said rod and with means normally closing said opening.

4. A valve mechanism of the character described, comprising a housing having a chamber therein and provided with an inlet to said chamber from a source of pressure fluid and with a plurality of outlets from said chamber, normally closed valve elements operatively associated with said outlets, said housing having a recess therein extending from said chamber opposite said inlet, a flexible diaphragm secured in said housing and extending across said recess and responsive to the pressure of the fluid in said chamber, and an equalizer member in said chamber and connected with said diaphragm to move therewith and operatively associated with said valve elements to open the latter upon movement of the diaphragm in one direction.

5. A valve mechanism of the character described, comprising a housing having a chamber therein and provided with a pair of aligned recesses extending from opposite sides of said chamber, said housing having an inlet from a source of pressure fluid communicating with one of said recesses and being provided with a plurality of outlets from said chamber, normally closed valve elements operatively associated with said outlets, a flexible diaphragm secured in said housing and extending across the other of said recesses and responsive to the pressure of the fluid in said chamber, an equalizer member in said chamber and operatively associated with said valve elements, and means connecting said member with said diaphragm to move therewith to open said valve elements upon movement of the diaphragm in one direction and including a part having sliding guiding contact with said one recess.

6. A valve mechanism of the character described, comprising a housing having a chamber therein, said housing being formed of two separable parts, means for securing said parts together, one of said parts being provided with an inlet to said chamber, the other of said parts being provided with removable plugs having pas-

sages therethrough constituting outlets from said chamber, said passages including valve seat portions, valve means carried by said plugs and normally engaging said valve seat portions, each of said parts of said housing being enclosed in a protective envelope, said envelopes when said parts are united and secured together constituting a sealed enclosure for said housing with the envelope containing the part provided with the outlets having means for attaching the valve mechanism to an inflatable raft or boat and provided with openings through which said plugs extend to a position wherein they will be located interiorly of the raft or boat when the mechanism is secured to the latter.

7. A valve mechanism of the character described, comprising a housing having a chamber therein and provided with an inlet to said chamber from a source of pressure fluid and with a plurality of outlets from said chamber, normally closed valve elements operatively associated with said outlets and each including a movable pin extending into said chamber, and means responsive to the pressure created in said chamber by the incoming pressure fluid for actuating mechanically said valve elements to open position simultaneously and identically and including a rigid element operatively associated with said valve pins and having bodily straight line movement in a path parallel to the path of movement of said valve pins.

8. A valve mechanism of the character described, comprising a housing having a chamber therein and provided with an inlet to said chamber from a source of pressure fluid and with a plurality of spaced outlets from said chamber, normally closed valve elements operatively associated with said outlets, said housing having a recess therein extending from said chamber and located intermediate said spaced outlets, a flexible diaphragm secured in said housing and extending across said recess and responsive to the pressure of the fluid in said chamber, and an equalizer member in said chamber and connected with said diaphragm to move therewith and operatively associated with said valve elements to open the latter upon movement of the diaphragm in one direction.

JOHN C. CROWLEY.
